TONSILLECTOME

Herman R. Grieshaber, Chicago, Ill., assignor to
 Grieshaber Manufacturing Company, Inc., Chi-
 cago, Ill., a corporation of Illinois

Application October 9, 1947, Serial No. 778,872

7 Claims. (Cl. 128—309)

1

This invention relates to tonsillectomes, more particularly to a tonsillectome which is adaptable for one-hand manipulation.

Various tonsillectomes have heretofore been proposed, which have been either too weighty in construction or awkward in design so as to make them unsuitable for one-hand manipulation. Also, often it has been found in performing an operation of this type with such an instrument that the work of the surgeon is obscured by bleeding of the patient while the tissue is being severed. Thus it is one of the objects of this invention to provide an improved tonsillectome which is sturdy in construction, simple in design, and readily adaptable to one-hand manipulation.

It is a further object of this invention to provide an improved tonsillectome which will thoroughly crush the tissue and prevent bleeding by the patient while a stump of the tonsil is being severed.

It is also a further object of this invention to provide an improved tonsillectome which can readily be disassembled for cleaning.

Further and additional objects will appear from the description, accompanying drawings, and appended claims.

In accordance with one embodiment of this invention, a tonsillectome is provided having an elongated body and a handle rigidly attached to the rear portion of said body. The handle is shaped to conveniently fit into the palm of the hand when grasped. Slidably mounted on said body are a crusher hemostat and a cutting blade which are guided at the forward end of said body. The forward end of said body has an opening which is adapted to allow the tonsil tissue to extend therethrough. Thus when the hemostat and blade are moved forwardly across the said opening, the tissue is first thoroughly crushed by the hemostat, whose forward end slightly leads that of the cutting blade, and then the cutting blade, while the tissue is thus held by the hemostat, is further moved forward to sever the stump of the tonsil.

For a more complete understanding of this invention, reference should now be had to the drawings wherein:

Fig. 1 is a side elevational view of the tonsillectome;

Fig. 2 is a top plan view of the tonsillectome showing the crusher hemostat and cutting blade partially extending across the opening in the body or frame member;

Fig. 3 is a fragmentary bottom view of the forward end of the frame member showing the posi-

2

tion of the hemostat relative to the cutting blade while moving across the opening in said forward end;

Fig. 4 is a fragmentary perspective view of the rear end of the hemostat and cutting blade showing the arrangement for moving said hemostat and cutting blade by the thumb of the surgeon's hand;

Fig. 5 is a fragmentary side elevational view showing the hemostat locked in its extreme forward position and the cutting blade moved to its extreme forward position after severing the tonsil tissue; and

Fig. 6 is a fragmentary sectional view of the forward end of the frame body showing the guide grooves for the hemostat and cutting blade when moving across the opening in said body.

Referring now to the drawings and more particularly to Fig. 1, a tonsillectome is shown comprising a substantially paddle-shaped, elongated body 10. The forward end 14 of the body 10 is enlarged and provided with an opening 12 through which the tonsil tissue to be severed protrudes, see Fig. 2. The outer edge of the end 14 is turned upwardly and slightly inwardly to form a flange 15, which serves as a guide for the forward ends of a hemostat 24 and a cutter blade 26. A narrow slit 19 is formed in the front end of flange 15 through which the cutting edge 36 of the blade 26 passes subsequent to traversing the opening 12.

The hemostat 24 is adapted to thoroughly crush the tonsil tissue extending through opening 12 before the tissue is severed by the blade 26 and thus prevents excessive bleeding during the severing operation. Further description of the hemostat and blade is reserved until later.

Mounted on the underside of the center portion 16 of body 10 is a downwardly and rearwardly extending handle 18. The handle is shaped so as to conveniently rest in the palm of a surgeon's hand. The upper end of the handle is bifurcated and embraces a section of the center portion 16 of body 10. The bifurcated end portions of the handle project above the upper, flat, smooth surface of the body 10, and serve as guides 33 for the blade 26.

Mounted on the rear end of body 10 and extending longitudinally therefrom, is a threaded stud member 20. Threadably engaging stud member 20 is a wing type holding nut 22 and a lock nut 28 having knurled collar 28'. Nuts 22 and 28 are readily removable from member 20 when the instrument is to be disassembled for

cleaning. The function of the holding and lock nuts will become apparent hereinafter.

Slidably mounted on the upper surface of body 10 is a relatively thin, substantially paddle-shaped, cutter blade 26. The enlarged forward end 26' of the blade is disposed within a guide groove or channel 32 formed in flange 15. The rounded forward edge of end 26' is sharpened to form a cutting knife or edge 36. The rear end portion of the blade is offset downwardly to form a thumb engaging member 56. An opening 52 is formed in member 56 through which stud member 20 extends. Blade 26 when actuated by the thumb of the surgeon can only move in a longitudinal direction relative to body 10 and across opening 12, due to the guiding effect of stud member 20, bifurcated ends 33 of handle 18, and the groove 32 formed in flange 15.

Superimposed on blade 26 and slidably mounted with respect to the blade and body as well is a relatively thin, substantially paddle-shaped hemostat 24. The enlarged, forward end 35 of the hemostat is disposed in a second guide groove or channel 30 formed in flange 15 above groove 32, heretofore described, see Fig. 6. The rear end portion of the hemostat is offset downwardly similar to that of blade 26, to form a thumb engaging member 54, which overlaps member 56 of the blade. Member 54, however, is shorter in length than member 56, thus the lower end of member 56 extends beneath member 54 thereby enabling the surgeon to conveniently move the blade forward independently of the hemostat and sever the tonsil tissue after the tissue has been thoroughly crushed by the hemostat. An opening 52 is likewise formed in member 54 through which stud member 20 extends. The center portion 49 of the hemostat is of slightly greater length than the center portion 59 of the blade, so that when the hemostat and blade are moved in unison forwardly along body 10 by the surgeon, the blunt rounded edge of the forward end 35 of the hemostat will lead slightly the cutting edge or knife 36 of the blade as they traverse the opening 12, see Fig. 3.

Positioned above hemostat 24 is a pawl 38 having a bow-spring shank portion, the rear end 39 of which is offset downwardly and is adapted to engage one of a series of ratchet teeth 37 formed on the upper surface of the center portion 49 of hemostat 24, see Figs. 1, 2, 4, and 5. A substantially U-shaped guide member 40 is mounted on the pawl adjacent rear end 39 thereof and embraces the center portion of the hemostat thereby preventing lateral movement of the pawl. Mounted on the underside of the forward end of the shank portion of the pawl is a downwardly extending stud 42. The stud extends through like, elongated, longitudinal slots 44 and 46 formed in hemostat 24 and blade 26, respectively.

The lower end 43 of the stud 42 is slightly oblong in cross section. An oblong-shaped opening 48 is formed in body 10 to receive the lower end 43 of the stud. Opening 48 is counterbored from the bottom and is provided with shoulders 53 which engage the end 43 of the stud when the pawl 38 is in its proper relative position with respect to the hemostat, as seen in Fig. 1. To allow the stud 42 to pass through slots 44 and 46 and opening 48 the pawl 38 must be initially turned at a right angle from the position shown in Fig. 2, and then swung to the position as shown whereupon the end 43 of the stud 42 engages shoulders 50, see Fig. 1.

The pawl 38 serves two primary functions; (1)

It prevents buckling of the hemostat when the hemostat is pushed into crushing engagement with the tonsil tissue, and (2) Once the hemostat is in crushing engagement with the tonsil tissue, the offset end 39 of the shank engages ratchet teeth 37 and temporarily holds fast the hemostat in its tissue-crushing position.

In using the instrument the surgeon grasps the handle thereof and positions the forward end 10 of the instrument in the patient's mouth so as to cause the tonsil tissue to extend through the opening 12. The surgeon then simultaneously moves the hemostat and blade forwardly along the body 10 until the tonsil tissue is thoroughly crushed by the blunt end of the hemostat, which leads the cutting edge of the blade as they traverse the opening 12, see Fig. 3. The surgeon effects this forward movement of the hemostat and blade by pushing with his thumb the downwardly extending member 54 of the hemostat or by threading holding nut 22 on the member 20 thereby causing the nut to abut member 54. Normally the member 54 is pushed by the thumb of the surgeon, whereupon the hemostat is temporarily held in its tissue-crushing position by the pawl as heretofore described. The holding nut 22 is then threaded on the stud member 20 until it abuts offset member 54. The locking nut 28 is then threaded on the member 20 until it abuts holding nut 22. The hemostat is then locked in its extreme forward or tissue-crushing position A, see Fig. 5. With the hemostat in this position the blade is then moved forwardly independently of the hemostat by the surgeon's thumb engaging the portion of offset member 56 extending beneath member 54 of the hemostat. Severance of the tonsil by the cutting edge 36 of the blade thereby results upon independent forward movement of the blade.

Certain modifications of the specific embodiment described are obvious and may be made without departing from the spirit and scope of this invention. For example, the handle may be adjustably-mounted on the body of the instrument so that the handle is capable of assuming various angular positions relative to the body 10, depending upon the conditions encountered in performing the operation.

Thus a tonsillectome has been provided which is capable of one-hand manipulation by the surgeon, is of sturdy, light-weight construction, and may be readily disassembled for cleaning.

While a particular embodiment of this invention is shown above, it will be understood, of course, that the invention is not limited thereto since many further modifications may be made and it is contemplated, therefore, that the appended claims shall cover any such modifications as fall within the true spirit and scope of this invention.

I claim:

1. An instrument of the class described comprising a frame member having a handle rigidly attached thereto and a forwardly extending body, a cutting blade and a crusher hemostat slidably mounted on said body, associated with said hemostat a ratchet catch for preventing rearward movement thereof when crushing the tissues engaged thereby, means extending rearwardly from said body and embraced by said blade and hemostat for guiding said blade and hemostat when moved lengthwise of said body, and means for securing said hemostat in the extreme forward position when manually moved to such position prior to the severing of the tissue by said blade.

2. An instrument of the class described comprising an elongated body, an elongated cutting blade and crusher hemostat slidably mounted on said body, said blade and hemostat having the rear end portions thereof angularly offset, and guide means, mounted on said body and rearwardly extending therefrom, embraced by the angular offset portions of said blade and hemostat.

3. An instrument of the class described comprising an elongated body, an elongated cutting blade and crusher hemostat slidably mounted on said body, said hemostat being disposed above the blade and the rear end portions of said blade and hemostat being offset downwardly, and guide means for said blade and hemostat provided at the forward and rear ends of said body, said rear end guide means being embraced by said offset end portions of said blade and hemostat.

4. An instrument of the class described comprising an elongated body, an elongated cutting blade and crusher hemostat slidably mounted on said body and adapted to be moved in a longitudinal direction with respect thereto, said blade and hemostat having the rear end portions thereof offset in a downward direction relative to said body, and guide means for said blade and hemostat extending rearwardly in a longitudinal direction from said body and projecting through said offset end portions.

5. An instrument of the class described comprising an elongated body, an elongated cutting blade slidably mounted on said body, an elongated hemostat disposed above said blade and slidably mounted thereon, said blade and hemostat having the rear end portions thereof offset in substantially a transverse direction, and means provided at the forward and rear ends of said body for guiding said blade and hemostat upon movement thereof in a longitudinal direction; said rear end guide means being embraced by the offset rear end portions of said blade and hemostat.

6. An instrument of the class described comprising an elongated body, an elongated cutting

blade and crusher hemostat slidably mounted on said body, said blade and hemostat having the rear end portions thereof offset downwardly with respect to said body, and guide means for said blade and hemostat mounted on the forward and rear ends of said body, said downwardly extending end portions of said blade and hemostat being in slidable engagement with said rear guide means.

10 7. An instrument of the class described comprising an elongated body having the forward end thereof provided with an opening, an elongated cutter blade slidably mounted on said body for forward and rearward movement lengthwise of said body, said blade having the rear-end portion thereof offset downwardly, an elongated hemostat disposed above said blade and slidably mounted on said body for forward and rearward movement lengthwise of said body, said hemostat having the rear-end portion thereof offset downwardly, guide means for said blade and hemostat extending rearwardly from said body and through an opening formed in each of the offset end portions of said blade and hemostat, and adjustable means engageable with said guide means and abutting the offset end portion of said hemostat for holding said hemostat in a relatively fixed forward position with respect to said body.
